UNITED STATES PATENT OFFICE.

WILLIAM J. McCARROLL, OF MELROSE PARK, PENNSYLVANIA.

MEANS FOR AUTOMATICALLY REGULATING THE DRAFT IN LOCOMOTIVE BOILERS.

Application filed March 10, 1921. Serial No. 451,227.

To all whom it may concern:

Be it known that I, WILLIAM J. McCARROLL, a citizen of the United States, residing at Melrose Park, in the county of Montgomery and State of Pennsylvania, have invented certain new and useful Improvements in Means for Automatically Regulating the Draft in Locomotive Boilers, of which the following is a specification.

10 My invention relates to means for automatically regulating the draft in locomotive boilers, and more specifically considered, it relates to improved means for breaking or reducing the vacuum in the smoke box of the locomotive at certain times, for the purpose of effecting certain economies in the operation of the locomotive, as well as to minimize the frequency of blowing off of the safety valve of the locomotive boiler.

20 The principal object of my invention is to provide means for automatically breaking or reducing the vacuum in the smoke box of the locomotive to thereby check the draft under certain conditions, and to thereby reduce the tendency of the boiler to blow off as frequently as now occurs. When a locomotive is standing, preparatory to the beginning of a run, it is desirable that the boiler pressure be maintained at a point 25 near the blow-off pressure, that is, near the pressure at which the safety valve is set, and it is also necessary under such conditions to keep the fire in an efficient condition ready for quick steaming, which is required when the locomotive is started on its run. The requirement to keep the locomotive under these conditions while standing in the station preparatory to a run, frequently results in the pressure at which the 30 safety valve is set being exceeded, whereupon the safety valve will blow off and considerable steam will be lost, together with the consequent loss of energy.

My present invention contemplates the 45 provision of a device which will automatically break the vacuum in the smoke box of the locomotive in an efficient manner when the boiler pressure approaches that at which the safety or blow-off valve is set, to the end that economy will be effected in the operation of the locomotive by obviating the frequent blowing off of the steam under the conditions above mentioned.

The nature and characteristic features of 50 my invention will be more readily understood from the following description, taken

in connection with the accompanying drawings forming part hereof, in which—

Figure 1 is a longitudinal central section of the front end of the locomotive provided 60 with a device embodying the main features of my present invention:

Fig. 2 is a transverse sectional view thereof taken approximately on the line 2—2 of Fig. 1;

Fig. 3 is a detail sectional view, enlarged, illustrating a type of automatic valve adaptable for use in connection with the device shown in Fig. 1; and

Fig. 4 is a horizontal plan view, enlarged, 70 taken approximately on the line 4—4 of Fig. 2.

Referring to the drawings, the particular embodiment of my invention therein shown is illustrated in connection with the front 75 end of a locomotive of an ordinary type, but it should be understood that the general structural details of the locomotive form no essential part of the present invention, but that the same is applicable to various types 80 of locomotives at present in common use.

As shown in the drawings, 5 is the smoke box of the locomotive in which the exhaust nozzle 6 is mounted in the bottom portion thereof beneath the stack 7, the arrangement 85 being such that the exhaust steam is projected upwardly from the exhaust nozzle 6 through the stack 7 to thereby create a partial vacuum in the smoke box 5, in the manner well known to those skilled in the art, 90 the effect of such vacuum being to create the necessary draft through the boiler tubes 8 to maintain the fire in the proper condition under the various conditions of operation of the locomotive.

Around the base of the exhaust nozzle 6 there is mounted a steam pipe 9 in the form of a ring having a plurality of outlet orifices 10 to permit jets of live steam to escape from the ring shaped pipe 9 around the base 95 of the exhaust nozzle. The ring shaped pipe 9 is connected by means of a pipe line 11 to an automatic valve 12, which in turn is connected to the top of the boiler so as to permit live steam to pass through the pipe line 105 11 to the ring shaped pipe 9, under certain conditions.

The automatic valve 12 may comprise any of the ordinary types of pop or safety valves so constructed and arranged that the steam 110 will only be permitted to pass when the pressure in the boiler exceeds a pre-determined

point, which point will preferably be a few pounds less than the pressure at which the main safety valve of the boiler is set to blow off. A type of valve suitable for this purpose is illustrated in Fig. 3 of the drawings, which, as there shown, comprises a housing 13, in which is mounted a valve disc 14, normally closing the passageway 15 extending from the boiler. The valve is normally held 10 on its seat by means of a spring 16, the tension of which may be adjusted by advancing or retracting the plug 17 which is threaded in the upper portion of the housing 13. The upper end of the housing is closed by means 15 of a suitable cap member 18, which also serves as a guide for the upper end of the valve stem 19. It should, of course, be understood that the particular construction of this valve forms no essential part of the invention, but that any type of valve may be employed which will accomplish the purpose hereinbefore mentioned, namely, permitting the steam to pass from the top of the boiler to the pipe line 11 when the pressure in the 20 boiler exceeds a pre-determined limit.

The operation of the device may now be readily understood. When the locomotive is standing idle, for example, in the station preparatory to a run, the fire is usually 30 maintained in a good condition for rapid steaming, with the consequent result that many times the pressure at which the main safety valve is set will be exceeded and the boiler will blow off, with the consequent loss 35 resulting therefrom. With the device of my present invention, the automatic valve 12 will come into operation when the boiler pressure approaches the limit fixed by the main safety valve, and will permit live steam 40 to pass from the top of the boiler through the pipe line 11 to the ring shaped pipe 9, and to thence escape through the outlet orifices 10, whereby the live steam will expand in considerable volume around the base of 45 the exhaust nozzle in the bottom of the smoke box 5, and thus effectually and effectively break the vacuum in said smoke box, and thereby reduce the draft through the flues 8. In this manner, the burning of the 50 fire in the furnace will be retarded, and thus the tendency of the same to cause a further increase in pressure of the steam in the boiler will be reduced.

It will be seen that there is thus provided 55 a simple and efficient device requiring little or no attention when once properly adjusted, which will automatically control the draft in the boiler, whereby the fire may be maintained in an efficient condition ready for 60 rapid steaming without causing frequent blowing off at the main safety valve, such as now usually occurs under the conditions above mentioned.

Having thus described the nature and 65 characteristic features of my invention,

what I claim as new and desire to secure by Letters Patent, is:

1. The combination in a locomotive having a boiler provided with a smoke box at the end thereof, a stack communicating therewith and an exhaust nozzle under the stack, of a device adapted to discharge steam in said smoke box and means for automatically supplying live steam from the boiler to the discharging device when the pressure in the boiler exceeds a predetermined limit.

2. The combination in a locomotive having a boiler provided with a smoke box at the end thereof, a stack communicating therewith and an exhaust nozzle under the stack, of a device adapted to discharge steam in the base of said smoke box, a pipe line extending therefrom and communicating with the top of the boiler, and automatic means for permitting live steam to pass from the boiler through said pipe line when the pressure in the boiler exceeds a predetermined limit.

3. The combination in a locomotive having a boiler provided with a smoke box at the end thereof, a stack communicating therewith and an exhaust nozzle under the stack, of a device adapted to discharge steam in the base of said smoke box, a pipe line extending therefrom and communicating with the top of the boiler, and an automatic valve interposed in said pipe line adapted to permit live steam to pass from the boiler through said pipe line when the pressure in the boiler exceeds a predetermined limit.

4. The combination in a locomotive having a boiler provided with a smoke box at the end thereof, a stack communicating therewith and an exhaust nozzle under the stack, of a device adapted to discharge steam in the base of said smoke box around said exhaust nozzle, a pipe line extending therefrom and communicating with the top of the boiler, and an automatic valve interposed in said pipe line adapted to permit live steam to pass from the boiler through said pipe line when the pressure in the boiler exceeds a predetermined limit.

5. The combination in a locomotive having a boiler provided with a smoke box at the end thereof, a stack communicating therewith and an exhaust nozzle under the stack, of a device having a plurality of outlet orifices adapted to discharge steam in the base of said smoke box, a pipe line extending therefrom and communicating with the top of the boiler, and an automatic valve interposed in said pipe line adapted to permit live steam to pass from the boiler through said pipe line when the pressure in the boiler exceeds a predetermined limit.

6. The combination in a locomotive having a boiler provided with a smoke box at

the end thereof, a stack communicating therewith and an exhaust nozzle under the stack, of a device having a plurality of outlet orifices adapted to discharge steam in the base of said smoke box around said exhaust nozzle, a pipe line extending therefrom and communicating with the top of the boiler, and an automatic valve interposed in said pipe line adapted to permit live steam to pass from the boiler through said pipe line when the pressure in the boiler exceeds a predetermined limit.

7. The combination in a locomotive having a boiler provided with a smoke box at the end thereof, a stack communicating therewith and an exhaust nozzle under the stack, of a pipe arranged adjacent said exhaust nozzle at the lower portion of the smoke box and having a plurality of outlet orifices adapted to discharge steam in the base of said smoke box, a pipe line extending therefrom and communicating with the top of the boiler, and an automatic valve interposed in said pipe line adapted to permit live steam to pass from the boiler through said pipe line when the pressure in the boiler exceeds a predetermined limit.

8. The combination in a locomotive having a boiler provided with a smoke box at the end thereof, a stack communicating

therewith and an exhaust nozzle under the stack, of a pipe at the lower portion of the smoke box and having a plurality of outlet orifices adapted to discharge steam in the base of said smoke box, a pipe line extending therefrom and communicating with the top of the boiler, and an automatic valve interposed in said pipe line adapted to permit live steam to pass from the boiler through said pipe line when the pressure in the boiler exceeds a predetermined limit.

9. The combination in a locomotive having a boiler provided with a smoke box at the end thereof, a stack communicating therewith and an exhaust nozzle under the stack, of a ring shaped pipe surrounding said exhaust nozzle at the lower portion of the smoke box and having a plurality of outlet orifices adapted to discharge steam in the base of said smoke box around said exhaust nozzle, a pipe line extending therefrom and communicating with the top of the boiler, and an automatic valve interposed in said pipe line adapted to permit live steam to pass from the boiler through said pipe line when the pressure in the boiler exceeds a predetermined limit.

In testimony whereof, I have hereunto signed my name.

WILLIAM J. McCARROLL.
